UNITED STATES PATENT OFFICE.

ISAAC E. SEXTON, OF WINCHESTER, MASSACHUSETTS.

SHEET-METAL CAN.

Application filed January 22, 1924. Serial No. 687,713.

To all whom it may concern:

Be it known that I, ISAAC E. SEXTON, a citizen of the United States, residing at Winchester, in the county of Middlesex and 5 State of Massachusetts, have invented new and useful Improvements in Sheet-Metal Cans, of which the following is a specification.

This invention relates to cylindrical sheet 10 metal shipping cans adapted to contain liquids, such as liquid paint, and to be tightly closed for shipment and storage.

The object of the invention is to provide certain improvements in the construction of 15 the open end portion of the can body, and the cover which closes said mouth, whereby the cover is adapted to be quickly and securely locked to the open end portion, without the formation of injurious angles or corners 20 on said end portion, and whereby the cover may be released by a simple prying operation.

I attain this object by the improvements hereinafter described and claimed.

25 Of the accompanying drawings forming a part of this specification,—

Figure 1 is a top plan view of a can embodying the invention.

Figure 2 is a section on line 2—2 of Figure 1.

Figure 3 is a fragmentary section on a larger scale, showing a portion of the can body without the cover.

Figure 4 is a fragmentary section showing 35 portions of the assembled body and cover, before the cover is locked.

Figure 5 is a fragmentary perspective view, showing the portions shown by Figure 4, the cover being locked.

40 Figure 6 is a section on line 6—6 of Figure 5.

Figure 7 is a view similar to Figure 4, showing the can body and cover provided with curled edges.

45 Figure 8 is a view similar to Figure 7, showing the cover locked to the body.

The same reference characters indicate the same parts in all the figures.

In the drawings, 12 represents the cylindrical body of a sheet metal can, closed at 50 one end by a suitable bottom (not shown), and open at the opposite end. Spaced below the open end is an annular cover seat 13, projecting inward from the internal surface 55 of the body and preferably integral therewith, the seat being a doubled annular flange,

one side of which faces upward as shown.

The portion 14 of the body above said seat, constitutes an annular cylindrical curb, having a continuous upper edge or end, and 60 adapted at its upper portion to be bent inwardly to form inwardly projecting inclined bosses 15, of which there may be two or more, four being shown by Figure 1. The bosses are spaced above the seat 13, and 65 overhang the cover seat. Each boss presents a rounded inner surface which is inclined inward and upward from the inner side of the curb. 16 represents a circular cover having an annular seating portion or zone 17, 70 conforming closely to the seat 13, and a marginal upwardly projecting annular flange 18, conforming to the internal surface of the curb 14.

The arrangement is such that the cover 75 may be inserted in the curb, as shown by Figure 4, until it bears on the seat 13, and may then be secured by forming the bosses 15, these being formed by any suitable means

adapted to bend the upper end of the curb inward at intervals, and form bosses which are inclined, as shown by Figures 2, 5, 6, and 8. The bosses overhang the upper edge of the flange 18, and their lower portions bear 80 on said edge and constitute stops, holding the cover down on the seat, and firmly locking the cover to the body. The width of the flange is such that when its upper edge is engaged by the bosses, the seating portion 17 is pressed closely against the seat 13, so 85 that a practically liquid-tight joint is formed between the seating portion and the seat.

The bosses include the upper edge or end 90 of the curb, and provide inwardly curved portions, without interrupting the continuity of the said upper edge or end, so that there are no sharp corners or angles liable to injure the hands.

The cover may be released by a thin-ended prying tool or lever 20, such as a 100 screw-driver inserted between a boss 15 and the upper edge of the flange 18, the latter constituting a fulcrum on which the lever is swung outward, to force the boss outward from its operative position. This operation, repeated at two or more of the bosses, 105 permits the removal of the cover. The inclination of the inner sides of the bosses renders them so flexible that they may be easily displaced by the prying action of the lever.

I prefer to form in the cover an angular

groove 21, concentric with the flange 18, one side of this groove forming a shoulder 22, which bears on the inner edge of the seat 13, and increases the area of the joint. The 5 groove stiffens the cover and minimizes liability of the indentation thereof by external pressure.

The upper edge of the curb 14 may have a bead 23, formed by curling the edge outward and downward. The upper edge of the flange 18 may have a corresponding bead formed by curling it inward and downward, as indicated at 24 (Figure 8). The outwardly projecting bead 23, may be bent inwardly at intervals by the operation of forming the bosses. The portions of the bead between the bosses constitute a circumferential ridge which cooperates with a ridge 25 at the lower end of the body, when the latter is being rolled on a floor. The inwardly projecting bead 24 facilitates the engagement of the tool 20 with a boss 15, as indicated by Figure 8.

As shown by Figures 5 and 6, the flange 18 may have inwardly offset portions 26, which are shorter than the bosses 15, and form openings or pockets for the reception of the end of a prying tool or lever 20, the upper edges of said portions forming fulcrums for the lever. The seat 13 is preferably inclined, to form, with the curb, a gutter adapted to hold a liquid joint-sealing composition 27, as shown by Figure 3.

I claim:

35 1. A can comprising a cylindrical sheet metal body having an inwardly projecting cover seat, an end portion of the body pro-

jecting above the seat and forming a flexible continuous cylindrical annular curb, the upper edge of which is of the same diameter 40 as the cylindrical body, a circular cover having an annular seating portion formed to bear on the seat, and a marginal upwardly projecting annular cylindrical flange bearing on the lower portion of the curb, the 45 upper portion of the curb projecting above the cover flange, and a plurality of inwardly projecting flange-confining bosses formed by inwardly bending the projecting upper portion of the curb, including the upper edges thereof, after the cover is deposited on the seat, said bosses having inclined inner sides overhanging the cover flange, the lower portions of said inclined sides engaging the upper edge of the cover flange to confine the 50 cover on the seat, the inclination of said sides rendering the bosses flexible and permitting a prying lever inserted between the cover flange and the boss, and fulcrumed on the flange, to exert outward pressure on the 55 boss and bend its inclined side and upper edge outward, thus releasing the corresponding portion of the cover and permitting it to be raised from the seat.

2. A can as specified by claim 1, the cover 60 flange being provided with inwardly offset pockets with which the said bosses coincide, each pocket forming a fulcrum spaced inward from the corresponding boss and permitting the insertion of a prying lever be- 70 tween the boss and the cover flange.

In testimony whereof I have affixed my signature.

ISAAC E. SEXTON.
